Specification for Design.

Patented Dec. 12, 1916.

Application filed October 24, 1916. Serial No. 127,504. Term of patent 3½ years.

To all whom it may concern:

Be it known that I, ALLIE S. FREED, a citizen of the United States, and a resident of the city of New York, borough of Manhattan, in the county and State of New York, have invented a new, original, and ornamental Design for an Embroidered Trimming, of which the following is a specification, reference being had to the accompanying drawing, forming a part thereof.

The figure is a plan view of the embroidered trimming showing my new design.

I claim:

The ornamental design for an embroidered trimming as shown.

ALLIE S. FREED.
